Daniel A. Carpenter,

ATTORNEY

UNITED STATES PATENT OFFICE.

ADOLPH GEERING, OF NEW YORK, N. Y.

DESIGN FOR A VESSEL-COVER.

SPECIFICATION forming part of Design No. 28,378, dated March 15, 1898.

Application filed September 4, 1897. Serial No. 650,682. Term of patent 7 years.

To all whom it may concern:

Be it known that I, ADOLPH GEERING, a citizen of the United States, residing at New York city, in the county and State of New York, 5 have invented and produced a new and original Design for a Vessel-Cover, of which the following is a specification, reference being had to the accompanying drawings, forming a part thereof.

10 Figure 1 of the drawings is a plan of a cover embodying the design, and Fig. 2 a side view thereof.

Similar reference-numerals designate like parts in both views.

15 This design relates to covers of culinary and other similar vessels; and the design consists of the new, useful, and original shape or configuration of the article of manufacture herein shown and described.

20 The leading or material feature of the design is the shape of an arm which projects

from the cover proper, the shape of this arm being characterized by the curvature of its outer portion backward and downward from its inner portion.

25 The main part 1 of this cover, or the cover proper, has the shape represented in the drawings. The projecting arm 2 has approximately the shape of a member of a hinge and a gun-trigger united, the hinge-like portion 30 20 of the arm being next to the part 1 of the cover and the trigger-like portion 21 extending outward from the portion 20 and curving downward behind it, as appears by Fig. 2.

Having thus described my design, what I 35 claim is—

The design for a vessel-cover, substantially as shown and described.

ADOLPH GEERING.

In presence of—

CHAS. COLEMAN MILLER,
ARTHUR F. THOMPSON.
